TAPE CUTTER FOR BAG CLOSING
MACHINESJacob J. Neuman, South Salem, N. Y., assignor to
United States Patent Development and Royalty
Company, South Salem, N. Y.

Application January 3, 1939, Serial No. 249,096

6 Claims. (Cl. 112—130)

This invention relates to tape cutters for bag closing machines and more particularly to a cutter for severing the paper tape sewed over the top of a filled bag for the purpose of sealing or closing the mouth thereof. In a sewing machine of this type, the paper tape is fed into the sewing machine through a folder which forms or folds the flat tape over the bag and when the entire top of the bag has been sewed it is necessary to sever the tape and thread in order to detach the bag from the sewing machine. At present, this is usually done manually with a knife and although there are some mechanical cutters on the market they are not only complicated and bulky but are unreliable and require frequent sharpening.

It is, therefore, a primary object of the invention to provide an inexpensive and reliable cutter of this type which is readily adaptable to existing sewing machines.

A further object is to provide such a cutter that requires no sharpening and which employs a quickly and easily replaceable blade of the inexpensive type used in safety razors, thus minimizing lost time due to shut downs which are experienced with existing cutters while they are being sharpened.

A further object is to provide a cutter which will cut close to the bag, minimizing the length of the paper tape protruding from the end thereof, improving the appearance of the package and affording economies in the amount of thread, tape, etc., used.

In the accompanying drawings wherein like numerals refer to like parts throughout.

Figure 1 is a perspective view showing the invention in application on a sewing machine.

Figure 1a is a front elevation showing a contact end of the presser of Figure 1 in the machine.

Figure 2 is an enlarged view of the cutter showing its relation to the sewing machine presser foot.

Figure 3 is a vertical section on the line 3—3 of Figure 2.

Figure 4 is a side elevation of Figure 3.

Figure 5 is a perspective view of an alternate embodiment using a solenoid.

Figure 6 shows an additional embodiment using an air cylinder.

Figure 7 is a horizontal section through the sewing machine 10 showing a still different embodiment.

Figure 8 is a detailed perspective view on an 55 adjustable.

enlarged scale of the contact end of the presser shown in Figure 1a.

A filled bag is delivered from the filling mechanism by means for instance of a conveyor like 5 the one shown at 48 in Figure 7. This conveyor 48 is situated to carry the filled bag through the sewing mechanism. In the sewing mechanism a tape is folded over the upright top of the bag so as to enclose the upper edges of the two sides and 10 a row of stitches is placed through the two sides of the bag and the two folded sides of the strip. The strip is fed continuously into the sewing mechanism and the sewing is done continuously in the usual manner. It is therefore necessary to sever the portion of the strip and the thread forming the stitches on a single bag so as to remove the bag. The most obvious means heretofore employed has been to cut the strip and thread manually by a knife, scissors or the like. Some cutters have also been incorporated into the sewing machine but those previously used have the objection of complexity and particularly of difficulty in sharpening the cutting edge whatever it is.

Referring now particularly to Figures 1 to 4, 10 designates the conventional sewing head which is driven from a belt 11 through a pulley 12. The belt 11 is driven by any suitable driving mechanism as will be well understood. The sewing head 10 contains a presser foot 13 which is carried on rods 14 which yieldingly press the foot against the tape 15 and the upper edge of the bag 16. The tape 15 is fed from a continuous source through the folding channel 36 which receives the flat tape and forms it over the upper edges of a bag 16 which is fed beneath the forming channel on the conveyor. The presser 13 therefore holds the tape 15 and the upper edges of the bag 16 in position for sewing by the feeder mechanism (not shown) in the usual manner. The moving of the bag 16 through the sewing machine 10 on a conveyor is shown in my Patent No. 1,823,283. In Figure 1 the bag 16 has been sewed and is emerging from the sewing machine 10. The cutting blade 17 is supported in close proximity to the tape 15 but out of contact therewith by means of the supporting plate 18 which, as shown in Figures 2 to 4, is secured to the bracket 19 by screws 37. The bracket 19 is in turn clamped on the presser foot rods 14 by means of a block 20 and a screw 21. By changing the position at which the bracket 19 is clamped on the rods 14 the normal distance between the blade 17 and the tape 15 is readily

According to the invention the blade 17 is of the readily replaceable wafer type similar to the blades used in safety razors. These blades have a very sharp cutting edge, are readily fastened to the supporting plate 18 and above all may be rapidly and economically replaced when the cutting edge becomes dull or broken. By preference the blades used are of the type having a longitudinal slot so that the attaching screws 22 which hold the blade to the supporting plate 18 make it possible to secure a limited vertical adjustment of the blade.

Severing of the tape and thread is accomplished by positioning a pivoted lever on the sewing head 10. This lever has two arms 23 and 24 and is pivoted on the pin 24' carried by the sewing head 10. The extremity of the arm 23 has a flattened portion 23A designed to engage against the strip and upper edge of the bag near the blade 17 and on the opposite side therefrom. A spring 30 is attached to the arm 24 at the eyebolt 26 and has its other end attached at 31 to the sewing head 10. The spring 30 tends by its traction to project the flattened end 23A against the tape and upper part of the bag to swing them against the cutting blade 17 so as to sever the thread and tape. The extent of swinging of the arms 23 and 24 is limited by a stud 32 positioned as desired on the sewing head 10.

Control of the device for severing the tape and thread is had by means of the rod 25 which is pivotally connected to the arm 24 at the eyebolt 26. The lower end of the rod 25 is pivoted to a link 27 which is pin connected to the shaft 28 journaled at 28' on a fixed part of the machine. A foot control lever 29 is pin connected to the opposite end of the shaft 28 and is positioned near the ground at a convenient point for operation by an operator's foot. Preferably, a pair of spaced collars 33 on the shaft 25 engage the switch arm 34 of the sewing machine motor switch 35 so that operation of the cutter is synchronised with the operation of the sewing machine motor. The motor leads 60 comprise the sewing machine motor control circuit in which the switch 35 connected thereto is interposed. With this control an operator may depress the pedal 29 and simultaneously start the sewing machine motor and withdraw the end 23A from engagement against the tape 15 and the upper part of the bag. The pedal 29 is held in depressed position until a bag is completely sewn and reaches the position of the bag 16 in Figure 1. Thereupon the operator releases the pedal 29 and the spring 30 swings the end 23A against the tape 15 and the top of the bag pressing it against the cutter 17 and severing the tape and the thread which forms the row of stitches. At the same time the spring 30 causes the rod 25 to move downwardly and the switch arm 34 is swung to circuit opening position thus stopping the sewing machine drive. The released bag may then be conducted away in any suitable manner, another bag brought to sewing position and the cycle repeated.

Figure 1a shows the contact end 23A in the machine. As shown in this figure, the arm 23 has at its lower end a curved contact portion 23A, the convex face of which is swung against the adjacent bag and tape when the presser is operated. With this type of contact end the upper portion of the tape is first presented to the cutting blade 17. The full pressure is therefore applied over a small portion of the tape 15 against the blade 17 so that cutting is accom-

plished more quickly and with less stress on the blade. Progressive swinging of the presser brings the lower portion of the tape against the lower part of the blade 17 and here again the full pressure is applied over a small portion of the tape. The result is that the tape 15 is cut from top to bottom instead of cutting it simultaneously across its whole width. This feature is of particular value since it serves to preserve the keenness of the blade 17 and thus extend its period of usefulness.

Referring now to Figure 5, a modified control for the severing mechanism is shown. In this form of the device the control rod 25' operates the switch arm 34 in the same manner. The rod 25' however does not connect with the arm 24 but this arm 24 is operated by a solenoid 38 which is connected by the wires 41 and 42 to the sewing machine switch 35'. The solenoid plunger 39 is connected by a link 40 to the eyebolt 26 and, as before, the traction spring 30 tends to swing the arms 23 and 24 into severing position. In this form of control the solenoid 38 will be energized along with the sewing machine motor so that the arms 23 and 24 will be held in inoperative position against the traction of the spring 30 as long as the motor is running. When, however, the motor is stopped by releasing the pedal 29 the solenoid 38 will be de-energized and the spring 30 will cause the end 23A to swing the tape 15 and bag 16 against the cutting blade 17 as before explained.

In Figure 6 the arms 23 and 24 are operated by an air cylinder 43 having the piston 44 and piston rod 45. The piston rod 45 is connected to the stud end of eyebolt 26 of the arm 24 by means of a link 40'. Air under pressure may be admitted through the pipe 46 to raise the piston 44 and swing the arm 24 against the traction of the spring 30. The application of air pressure through the pipe 46 is controlled by means of an electro-pneumatic valve 35'' which is operated by the control rod 25''. The operation of this pneumatic severing device is the same as the previously described two devices.

Where the arrangement permits and the bag does not have a lining which must be sewed separately, the apparatus may be as shown in Figure 7. In this form of the device there is no pushing mechanism at all but a curved bracket 47 is placed along the conveyor 48 so as to strike the upper part of the bag and topple it over as it is carried by the conveyor 48. It will be seen that the manner in which the bag is toppled over causes the tape 15 to fall against the cutting edge of the blade 17 with the weight of the bag so that the tape and thread are severed and the bag 16 falls onto a suitable conveyance such as the conveyor 49 and is disposed of. The guide 41 is positioned at a distance from the sewing head 10 to insure that the trailing edge of the bag top is clear of the blade 17.

It is obvious that various changes and modifications may be made in the details of construction and design of the above specifically described embodiment of this invention without departing from the spirit thereof, such changes and modifications being restricted only by the scope of the following claims.

What is claimed is:

1. In combination with a bag sewing machine having a presser foot and rods supporting the presser foot, a thin replaceable stationary cutting blade, a support for said blade, a clamp to adjustably connect said blade support to the

rods to position said blade adjacent said presser foot and adjacent the bag, and pressing means for engaging said bag with said blade thereby severing the tape and thread sewn over the mouth of the bag leaving substantially no surplus tape attached thereto.

2. A tape and thread cutting device in combination with a bag sewing machine having a presser foot and rods supporting the presser foot, said device comprising a thin replaceable stationary cutting blade, means to connect said blade to said rods to support said blade adjacent said presser foot and adjacent one side of the bag, pivoted pressing means mounted adjacent the opposite side of said bag from said blade, spring means for moving said pressing means in one direction to rock said bag against said blade to sever the tape and thread sewn thereon, control means for said sewing machine, and means coordinated with said control means for moving said pressing means in the opposite direction, to maintain the latter out of contact with said bag during operation of the sewing machine.

3. A tape and thread cutting device in combination with a sewing machine for sewing the tape over the mouth of a bag, said sewing machine having a presser foot and rods supporting said foot, said cutting device comprising a thin replaceable stationary blade mounted on a support connected to said rods adjacent said presser foot and said bag, a presser arm pivotally and separately mounted on the opposite side of said tape from said blade, said presser arm having a blunt convex contact surface, and means for operating said presser arm to press the tape against said blade, said convex contact surface thereby causing said blade to slice said tape progressively from top to bottom.

4. In apparatus for closing bags including a sewing machine for sewing tape over the mouth of each bag, and a conveyor for feeding the bags through the sewing machine; a tape and thread cutting device comprising a thin stationary cutting blade mounted transversely to the direction of movement of the conveyor adjacent the delivery side of said sewing machine and adjacent one side of the sewed tape, a pivoted member mounted adjacent the opposite side of said tape and movable transversely to the direction of movement of the conveyor, spring means normally urging said member in one direction to

rock said bag towards said cutting blade, controllable means operatively connected to said member and operable to move the latter in the opposite direction against the tension of said spring means to maintain said member out of contact with said bag, and means for controlling the operation of said last named means to thereby control severance of the sewed tape by said cutting blade.

5. In apparatus for closing bags including a sewing machine for sewing tape over the mouth of each bag, and a conveyor for feeding the bags through the sewing machine; a tape and thread cutting device comprising a thin stationary cutting blade mounted transversely to the direction of movement of the conveyor adjacent the delivery side of said sewing machine and adjacent one side of the sewed tape, a pivoted member mounted adjacent the opposite side of said tape and movable transversely to the direction of movement of the conveyor, spring means normally urging said member in one direction to rock said bag towards said cutting blade to thereby sever the sewed tape, a solenoid operated plunger operatively connected to said member and operable upon energization of the solenoid to move said member in the opposite direction against the tension of said spring means, and means for selectively energizing and de-energizing the solenoid of said plunger.

6. In apparatus for closing bags including a sewing machine for sewing tape over the mouth of each bag, and a conveyor for feeding the bags through the sewing machine; a tape and thread cutting device comprising a thin stationary cutting blade mounted adjacent the delivery side of said sewing machine and adjacent one side of the sewed tape, a presser member mounted adjacent the opposite side of said tape and movable transversely to the direction of movement of the conveyor, spring means normally urging said presser member in one direction to rock each bag towards said cutting blade to thereby sever the sewed tape, a control rod operatively connected to said presser member and operable to move the latter against the tension of said spring means to maintain said presser member out of the path of movement of each bag, and means for actuating the said control rod.

JACOB J. NEUMAN.
